UNITED STATES PATENT OFFICE.

WILLIAM CHALLINOR, OF CLARKSBURG, WEST VIRGINIA, ASSIGNOR TO THE D. E. McNICOL POTTERY COMPANY OF WEST VIRGINIA, OF CLARKSBURG, WEST VIRGINIA, A CORPORATION OF WEST VIRGINIA.

DESIGN FOR A PLATE OR SIMILAR ARTICLE.

Application filed August 26, 1926. Serial No. 18,884. Term of patent 14 years.

To all whom it may concern:

Be it known that I, WILLIAM CHALLINOR, a citizen of the United States, residing at Clarksburg, in the county of Harrison and State of West Virginia, have invented a new and ornamental Design for a Plate or Similar Article, of which the following is a specification, reference being had to the accompanying drawings, forming a part thereof.

In the accompanying drawing the figure is a plan view of a plate showing my new design.

I claim:

The ornamental design for a plate or similar article, as shown.

WILLIAM CHALLINOR.
